(57) **CLAIM**

The ornamental design for an LED lamp housing, as shown and described.

DESCRIPTION

FIG. 1 is a perspective view of an LED lamp housing showing my new design.

FIG. 2 is a front elevational view thereof.

FIG. 3 is a rear elevational view thereof.

FIG. 4 is a left-side, elevational view thereof.

FIG. 5 is a right-side, elevational view thereof.

FIG. 6 is a top plan view thereof; and,

FIG. 7 is a bottom plan view thereof.

The broken lines shown in the drawings form no part of the claimed design.
